(57) **CLAIM**

The ornamental design for a gas probe holder, as shown and described.

DESCRIPTION

FIG. 1 is a front perspective view of a gas probe holder showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a front perspective view thereof, shown with a hook and loop fastener strap.

The broken line showing of portions of a gas probe holder in FIGS. 1 through 8 is for the purpose of illustrating environmental structure and forms no part of the claimed design.
